UNITED STATES PATENT OFFICE.

JAMES R. VIZE, OF EVANSVILLE, INDIANA.

FLYING APPARATUS.

1,012,767.

Specification of Letters Patent. Patented Dec. 26, 1911.

Application filed May 25, 1911. Serial No. 629,400.

To all whom it may concern:

Be it known that I, JAMES R. VIZE, a citizen of the United States, residing at Evansville, in the county of Vanderburg and State of Indiana, have invented certain new and useful Improvements in Flying Apparatus; and I do declare the following to be a full, clear, and exact description of the invention, such as will enable others skilled in the art to which it appertains to make and use the same.

This invention relates to improvements in flying apparatus.

One object of the invention is to provide an apparatus of this character comprising an improved construction and arrangement of propelling device adapted to be secured to the arms and feet of the aviator whereby the device may be effectually operated.

With this and other objects in view the invention consists of certain novel features of construction, combination and arrangement of parts as will be more fully described and particularly pointed out in the appended claims.

In the accompanying drawings: Figure 1 is a perspective view of the apparatus showing the application of the same; Fig. 2 is a perspective view of one of the foot propelling devices; Fig. 3 is a similar view of one of the arm propelling devices; Fig. 4 is a cross sectional view of the arm propelling device shown in Fig. 3. Fig. 5 is an inner end view of the foot propelling device shown in Fig. 2.

In the embodiment of the invention I provide arm propelling devices 1 and foot propelling devices 2. The arm propelling devices are in the form of planes and comprise substantially elliptical shaped open frames 3 which may be formed of any light, strong material and which are provided between their inner and outer ends with transversely disposed cross bars 4, said bars being secured to the frame in any suitable manner. On the bars are arranged centrally disposed hand grips 5 which are in the form of plates having arranged therein slots 6 through which the fingers of the hands are passed in grasping the grips as shown in Fig. 1 of the drawing. On the inner ends of the frames 3 are secured right angularly projecting arm plates 7 in which are formed arm holes 8 through which the arms are inserted and by means of which the inner end of the

plane is firmly secured in position for operation. The frames 3 are covered or have arranged therein a filling 9 formed of any suitable fabric, the edges of which are preferably secured to the frame by sewing or lacing as shown at 10. The foot propelling devices are also in the form of planes comprising substantially elliptical shaped frames 11.

The frames 11 are braced by transverse upwardly curved bars 12 arranged across the frames as shown. The inner ends of the frames are secured to the foot plates 13 which are preferably of foot shape and have secured to the toe and heel portions thereof upwardly projecting inwardly curved ankle bars 14 the upper ends of which are connected to a substantially semi-circular leg engaging plate 15 which is adapted to fit around the outer sides of the legs and which are fastened in position by straps 16. The straps 16 are adapted to be buckled around the inner sides of the legs as shown thus securely fastening the planes 2 to the feet and legs of the aviator. The leg engaging plate 15 is further braced and strengthened by inclined brace bars or rods 16' which are connected thereto at their inner ends and at their outer ends are connected with the outer ends of the frames 11 as shown. The frames 11 are covered with or have arranged therein a filling 17 of fabric or any suitable material, said filling being preferably sewed or laced to the frame and is held up from engagement with the ground by the curved brace bars 12. By thus securing the filling to the brace bars 12 the same is also made to concave or bag and thus form pockets which catch the air and make these propelling devices more effective.

In connection with the propelling devices 1 and 2 I provide a suitable sustaining device which is preferably in the form of a balloon 18 and is confined in a net 19 and secured by cords 20 to an attaching belt 100 or band 21 adapted to be buckled around the body of the aviator at any suitable position. By providing the balloon or similar means for sustaining the weight of the aviator the arm and foot planes may be employed solely for propelling purposes and are operated by moving the arms and legs somewhat in the manner in which they are moved in swimming. By this arrangement the aviator may fly high or low or may stop.

and remain at one position in the air when desired.

From the foregoing description taken in connection with the accompanying drawings, the construction and operation of the invention will be readily understood without requiring a more extended explanation.

Various changes in the form, proportion and the minor details of construction may 10 be resorted to without departing from the principle or sacrificing any of the advantages of the invention as defined in the appended claims.

Having thus described my invention, what 15 I claim is:

1. In a flying apparatus, a pair of arm operated propelling devices and a pair of foot operated propelling devices, said foot propelling devices comprising open frames, 20 upwardly curved cross bars arranged in said frames, foot plates secured to the inner ends of the frames, ankle bars secured to said foot plates, leg plates secured to the upper ends of said ankle bars, means to fasten said plates to the legs of the aviator, 25 brace rods to connect the outer ends of the frames with said plates, and a filling ar-

ranged over said frames and connected to said cross bars to form concaved planes.

2. In a flying apparatus a pair of arm 30 operated propelling devices, foot propelling devices comprising elliptical planes, foot plates arranged transversely of said planes at the inner ends thereof, means to secure said plates to the legs of an aviator, and 35 means to sustain the weight of an aviator in the air.

3. In a flying apparatus a pair of arm operated propelling devices, foot propelling devices comprising elliptical planes, foot 40 plates arranged transversely of said planes at the inner ends thereof, brace rods connected at one end with the leg engaging means of said foot propelling devices and at their other ends with the outer ends of said 45 elliptical planes.

In testimony whereof I have hereunto set my hand in presence of two subscribing witnesses.

JAMES R. VIZE.
